US00D813185S

(12) **United States Design Patent** (10) Patent No.: **US D813,185 S**
(45) Date of Patent: ** *Mar. 20, 2018

(54) **MOBILE PHONE**

(71) Applicant: **Huawei Device (Dongguan) Co., Ltd.**,
Dongguan (CN)

(72) Inventors: **Guoping Wu**, Shenzhen (CN); **Haiqi Zhang**, Shenzhen (CN); **Wensi Li**, Shenzhen (CN)

(73) Assignee: **Huawei Device (Dongguan) Co., Ltd.**,
(CN)

(*) Notice: This patent is subject to a terminal disclaimer.

(**) Term: **15 Years**

(21) Appl. No.: **29/556,518**

(22) Filed: **Mar. 1, 2016**

Related U.S. Application Data

(63) Continuation of application No. 29/490,964, filed on May 15, 2014, now abandoned, which is a continuation of application No. 29/451,468, filed on Apr. 2, 2013, now Pat. No. Des. 718,268.

(57) **CLAIM**

The ornamental design for a mobile phone, as shown and described.

DESCRIPTION

FIG. 1 is a front perspective view of a mobile phone showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The outermost broken lines shown in the figures that are immediately adjacent to the claim represent the bounds of the claim while all other broken lines are directed to environment; the broken lines form no part of the claimed design.

1 Claim, 4 Drawing Sheets
